UNITED STATES PATENT OFFICE.

ADOLPH R. BROCKSMITH, OF ST. LOUIS, MISSOURI.

REAR-AXLE TRUSS.

1,153,996.

Specification of Letters Patent. Patented Sept. 21, 1915.

Application filed December 7, 1914. Serial No. 875,745.

To all whom it may concern:

Be it known that I, ADOLPH R. BROCKSMITH, a citizen of the United States residing in the city of St. Louis and State of Missouri, have invented a new and useful Rear-Axle Truss, of which the following is a specification:

This invention relates to axle trusses, and the object of the invention is to provide a truss for strengthening and supporting sectional axle-housings so as to support or strengthen the entire housing, and prevent weakening at any of the points of connection between the various sections of the axle-housing.

With the foregoing and other objects in view I have illustrated a preferred embodiment of the invention in the accompanying drawings in which—

20. Figure 1 is an elevation of a sectional axle-housing having my improved truss connected therewith. Fig. 2 is a detail view illustrating one of the clamp brackets applied to the axle-housing so as to reinforce and strengthen the connection between two connecting portions of the sectional housing. Fig. 3 is a sectional view approximately on the line 3—3 of Fig. 2, viewed in the direction of the arrow. Fig. 4 is an 30 outer side elevation of one of the clamping brackets removed from the axle-housing.

In the embodiment in which I have illustrated my invention the axle-housing includes the two end sections 1 having radial flanges 2. A disk 3 is integral with the outer ends of the sections and with the flanges 2, said disk being effective to retain the brake bands on the brake-band wheels 4. The outer ends of the tubular sections 1 of the axle-housing extend into the inner ends of the tubular sections 1, and said sections are rigidly united by rivets 6, the heads of which form a substantial annular series of projections around the tubular sections 1 adjacent to the inner ends thereof. Preferably the sections 1 are extended within the sections 1 to or beyond the point at which the flanges 2 begin, so that the sections 1 and 5 are telescoped one within the other a sufficient distance to receive the clamping brackets upon the telescoped portions thereof.

Upon each of the tubular sections 1 is mounted a clamping bracket, said brackets being mounted between the annular series of projections 6 and the flanges 2, and em-

bracing the telescoping portions of the tubular sections 1 and 5. Each clamping bracket comprises an arcuate strap 7 adapted to be clamped upon one of the sections 1 between the flanges 2 and the projections 6, the ends of said strap being on opposite sides of the axle-housing. The ends of the strap 7 comprise threaded round extensions 8 connecting with the flat portion of the strap 7 by means of reinforcing ribs or enlargements 9. Each bracket includes a coöperating member adapted to clamp against the under side of the extension 1. In the form shown the coöperating member comprises a casting including an arcuate portion 10 adapted to bear against the under side of the tubular part 1, being seated between the projections 6 and the inner edges of the flanges 2. The projections 6 in coöperation with the clamping action of the bracket, prevent slipping of the bracket when the truss rod is tightened. On each end of the arcuate portion 10 is a flat portion 11, said portions being in the same plane and each being provided with a hole 12 to receive the round ends 8 of the strap. Releasable nuts 13 are screwed on the threaded ends 8 below the flat portions 11, and said nuts are adjustable to clamp the two portions of the clamping bracket firmly and rigidly in position. Since both members of the clamping bracket are secured between the inner edges of the flanges 2 and the projections 6 it will be understood that the tubular portions 5 of the housing extend into the tubular members 1 beyond the outer edges of the brackets, so that when the brackets are clamped in position the telescoping members of the housing are firmly clamped together and are strengthened and reinforced by the clamps. The lower side of the arcuate portion of the lower member of each bracket is provided with an integral depending part 14 at the outer edge of the lower portion of the bracket. Walls or flanges 15 integrally connect the side edges of the depending portion 14 with the central part of the arcuate portion of the lower member of the bracket, said two walls or flanges being spaced apart to permit the truss rod to extend between them. The inner edge of the arcuate portion of the lower member of the bracket is provided with a depending flange 16, and depending flanges 17 extend laterally from the walls or flanges 15 at the opposite edge of the arcuate portion of the

lower member of the bracket. The depending portion 14 of each bracket is provided with a hole 18 midway between the walls 15, said holes 18 being arranged to receive the outer ends of the truss rod 19 in the manner shown. The truss rod 19 has its outer ends passing through the holes 18 and is provided with releasable nuts 20 adjustable on the threaded ends of said rod and arranged to bear against the flat outer faces of the depending portions 14 of the brackets, whereby said truss rod may be firmly secured in position.

As illustrated in Fig. 1 the inner ends of the housing members 5 are formed with enlarged portions 21, the abutting edges of which are secured together, but which, under the constant strain and vibration to which the parts are subjected, are liable to become weakened and so impair the efficiency of the device. The truss rod 19 has its central portion curved downwardly and bears against the under side of the enlarged housing 21, so that when the nuts 20 are tightened against the depending portions 14 of the clamping brackets the central housing 21 will be firmly supported.

From the foregoing it will be understood that I have provided an efficient device of the character described in which the clamping brackets reinforce and strengthen the connection between the central housing members and the lateral housing members, and that it is impossible for the clamping brackets to slip from their position because of the projections 6 and the flanges 2 which coöperate with the clamping action of the brackets to retain them in rigid permanent adjustment. Further, the construction of the brackets themselves, in the specific form described contribute to the superior efficiency of the device.

Having described my invention what I claim is:

1. The combination with outer housing members, inner housing members extending into said outer housing members, elements fastening said outer and inner housing members together and extending beyond the outer surface of said outer members, and enlarged portions on said inner housing members in connection with each other, of clamping brackets clamping said outer housing members upon the inner housing members and having their inner edges bearing against said elements whereby inward movement of said brackets is prevented, depending projections on the outer edges of said clamping brackets, reinforcing walls uniting said depending projections with the inner portions of said brackets, and a truss rod having its ends connected to said de-

pending portions between said walls and having its central portion engaging against said enlarged portions of said inner housing members.

2. In an axle truss, a clamping bracket comprising an arcuate strap, round threaded projections on the ends of said strap, a co-operating member having an arcuate portion, flat portions on the ends of said arcuate portion having holes through which said round threaded projections extend, a depending projection integral with said arcuate portion, wall portions integral with said depending projection and with said arcuate portion, and a passage in said depending projection intermediate of said wall portions.

3. In an axle truss, a clamping bracket comprising a lower member including an arcuate portion adapted to bear against the axle-housing, flat projections on the ends of said arcuate portion provided with holes, a depending projection integral with one edge of said arcuate portion, parallel wall portions integral with said depending projection and with said arcuate portion and extending from said projection to points adjacent to the opposite edge of said arcuate portion, a depending flange integral with the opposite edge of said arcuate portion, a passage in said depending projection intermediate of said wall portions, an arcuate strap arranged to embrace the axle-housing, round threaded projections on the ends of said strap extending through the holes in said flat portions, and nuts threaded on said projections below said flat portions.

4. The combination with telescoping axle-housing members, and clamping brackets clamped around the outer housing member effectively to compress the same upon the inner housing member, of a depending projection at the outer edge of each of said clamping brackets, parallel wall portions integral with each of said depending projections extending toward the inner edges of said brackets, passages in said depending projections intermediate of said wall portions, a rod extending between said wall portions and through said passages, clamping nuts on said rod adjustable to hold said rod tight between said brackets, and means on the outer telescoping members preventing said clamping brackets from slipping toward each other.

In witness whereof, I have signed this specification in the presence of two subscribing witnesses.

ADOLPH R. BROCKSMITH.
